UNITED STATES PATENT OFFICE.

SAMUEL HOWARD STOTT, OF FULLWOOD, ENGLAND, ASSIGNOR TO THE STOTT GARDEN IMPLEMENT COMPANY, OF NEW YORK, N. Y.

LAWN-SPRINKLER.

SPECIFICATION forming part of Letters Patent No. 515,625, dated February 27, 1894.

Application filed June 2, 1893. Serial No. 476,356. (No model.)

To all whom it may concern:

Be it known that I, SAMUEL HOWARD STOTT, of Fullwood, in the county of Preston, England, have invented a new and Improved 5 55
5 Lawn-Sprinkler, of which the following is a full, clear, and exact description.

The object of the invention is to provide a new and improved lawn sprinkler, which is simple and durable in construction, very effective in operation, conveniently cleaned, not liable to get clogged up, and arranged to finely divide the water and discharge the same in sprays, covering the ground uniformly in a circular area of which the supporting post is the center.

The invention is embodied in the construction and combination of parts hereinafter described.

Reference is to be had to the accompanying 20 drawings, forming a part of this specification, in which similar letters of reference indicate corresponding parts in all the figures.

Figure 1 is a side elevation of the improvement as applied. Fig. 2 is an enlarged plan 25 view of the same. Fig. 3 is a sectional side elevation of part of the improvement on the line 3—3 of Fig. 2. Fig 4 is an inverted plan view of the cover plate; and Fig. 5 is a plan view of the cup.

30 The improved lawn sprinkler is provided with a pipe A carrying at its lower end a T B supporting a coupling C, connected with the supply hose D leading from a suitable source of water supply. The lower end of the T B 35 is closed by a point or spade E arranged in alignment with the pipe A and adapted to be forced into the ground so as to support the pipe A in a vertical position. See Fig. 1.

On the upper end of the pipe A is screwed 40 or otherwise secured, a cup F formed with a beveled top edge F' on which is adapted to be seated a like beveled edge G', of a flat cover plate G formed with an enlarged central aperture through which passes a bolt H secured on 45 a spider I, whose ends abut an annular shoulder formed in the interior of the cup.

On the outer end of the bolt H screws a 50 hand nut J having an ornamental shape and serving to hold the cover plate G with its beveled edge G' firmly seated on the beveled

edge F' of the cup F. One of the two contacting beveled edges F' or G, is provided with radial grooves open at the ends and closed at the open side by the opposite non-grooved beveled edge, so as to form jet apertures along the lines of the grooves for the exit of the water passing into the cup F from the pipe A under pressure.

As illustrated in the drawings, the beveled edge F' is the non-grooved one, while in the 60 beveled edge G' of the cover plate G are formed the radial grooves G², through which passes the water in jets as before explained. In the cover plate G are also arranged angular discharge openings G³, each made with 65 two concentric bores of which the inner bore is considerably larger in diameter than the outer bore, as plainly shown in Figs. 2, 3 and 4. This construction enables the water to discharge with much greater force than if the 70 bores were of uniform diameter.

Now, it will be seen that when the several parts are in the position shown in Figs. 1 and 3, the cover plate G is firmly held to its seat on the beveled edge F' by the nut J screwing 75 on the bolt H and abutting on the top of the said cover plate. Now, when water under pressure passes through the hose D, coupling C, T B, into the pipe A and from the latter into the cup F, then the water passes through 80 the grooves G² and the apertures G³ under considerable pressure, whereby the water is finely divided into jets, of which the jets formed by the grooves G² cover the ground in a circle, while the individual jets of water 85 passing through the apertures G³ are slightly inclined and come down onto the ground within the circle formed by the other jets passing through the grooves G². By this arrangement the entire circular area around the pipe 90 A is saturated with water. By enlarging the inner bore of the openings G³, a water reservoir is formed for each opening, which insures a continuous passage of water through the smaller outer bore of the opening under 95 full pressure of the water supply. It will be seen that by this arrangement the cover plate G can be readily removed by simply unscrewing the nut J and lifting the plate off the bolt H, for conveniently cleaning the in- 100

terior of the cup F, the grooves G² and openings G³, in case they should become clogged by sand or other impurities carried by the water.

5 Having thus fully described my invention, I claim as new and desire to secure by Letters Patent—

In a lawn sprinkler, the combination of the cup, and its cover having correspondingly beveled edges between which are discharge

openings, G², the said cover being provided with an inner circle of apertures, G³, which are inclined at a less angle than said openings, and formed of two differential aligned bores, as shown and described, to operate as 15 specified.

SAMUEL HOWARD STOTT.
